EPO. 3

James A. Maloney
INVENTOR

BY *Victor J. Evans*

Alfred J. Br
WITNESS:

UNITED STATES PATENT OFFICE.

JAMES A. MALONEY, OF SCRANTON, PENNSYLVANIA.

SAFETY-RAZOR AND STROP.

1,381,724.

Specification of Letters Patent. Patented June 14, 1921.

Application filed May 18, 1920. Serial No. 382,234.

To all whom it may concern:

Be it known that I, JAMES A. MALONEY, a citizen of the United States, residing at Scranton, in the county of Lackawanna and 5 State of Pennsylvania, have invented new and useful Improvements in Safety-Razors and Strops, of which the following is a specification.

This invention relates to safety razors

10 and it has more particular reference to that type of device which is combined with a holder or casing including a mirror whereby the progress of the shave can be conveniently observed.

15 The main object of my invention is to provide a combined safety-razor, sharpener and an unbreakable mirror which when not in use are neatly and compactly housed in a small case that can be conveniently carried

20 in the vest pocket.

Another object is to provide a device of the nature specified which is sanitary in every respect.

Still further this invention comprehends 25 many new and useful features or objects relating to the blade holder, means for storing a supply of new blades, the means for holding the blade in position relative to its holder, and the means for stropping or 30 sharpening the blade.

With the foregoing objects in view my invention consists essentially in the novel features of construction, combinations and arrangements of parts hereinafter more 35 fully described and then specifically defined by the appended claims.

In the further disclosure of the invention reference is to be had to the accompanying 40 sheet of explanatory drawings constituting a part of this specification and in which like characters of reference designate the same or similar parts in all the views.

Figure 1— is a plan view of my improved safety razor and stropping or sharpening 45 device with the inclosing casing shown in open position.

Fig. 2— is a transverse vertical section of the same.

Fig. 3— is an enlarged detail plan view 50 of the blade holder and its associated parts; and,

Fig. 4— is a miniature perspective view of the device with the blade holder in position ready for shaving.

55 Referring to the drawings the numeral 10, designates a small rectangular casing or

box of appropriate material such as thin sheet metal and which has hinged to one of its longer sides a cover or lid 11, in which is securely held by spring clips 12, a mirror 13 of unbreakable material and said mirror is provided with a hole 14 by means of which it can be hung up or suspended in a convenient position during the operation of shaving.

65

Longitudinally of one side of the casing or box 10 and revolvably mounted in bearings 15 is a shaft or spindle 16 on which is securely fixed a stropping roller 17 of any appropriate material, and it is to be noted 70 that the shaft 16 is extended at one end to project beyond an inner wall or end piece 18 of the casing or box 10. Slidably mounted on the outer or projecting end of the shaft or spindle 16 and connected thereto 75 by a pin and slot connection 19 is a sleeve 20 which carries an arm 21 to the free end whereof is hinged at 22 a handle 23. Thus it will be seen on reference to the dotted lines in Fig. 1 that when the sleeve 20— 80 arm 21—and handle 23 are not extended for use they can be collapsed or folded compactly down into the cellular portion 24 of the case 10 and be closed therein by the end flange or lip 25 of the lid or cover 11. 85

Hinged to the upper edge of the aforesaid end wall 18, at 26 is a plate or leaf 27 and below this plate or leaf are provided spaced spring tongues 28 between which and said plate or leaf 27 are stored a supply of 90 blades 29, depending flanges or lips 30 preventing their accidental displacement. This plate or leaf 27 is also provided on its upper end edge remote from the hinge 26 with a spring tongue 31 which grips the adjoining 95 end wall of the box or casing 10 and maintains said leaf or plate in closed down position when it is not desired to take out a new blade 29 for use.

The blade holder 32 consists of a sheet of 100 appropriate material such as thin metal and it is formed or stamped up with a scalloped and turned over longitudinal edge 33 which in use constitutes the bearing surface for the cutting edge of the blade 29, and the ends 105 of said holder 32 are somewhat upset or flanged at 34 to constitute retaining means for correspondingly shaped ears on the ends of the blade 29. The longitudinal edge 35 remote from the scalloped part 33 is also 110 similarly upset or flanged so that the blade 29 is also effectively prevented from falling

out of the holder 32 when in use. To provide a simple and effective means for locking the blade 29 to the holder 32, I preferably pivot at one end of the latter by a pin 36 a strip or stub 37 to the free end whereof is hinged at 38 a locking member 39 provided on the face folding down over the blade 29 with spring clamps 40, and at the free end of said locking member 39 I form a turned over lip 41 which is adapted to be passed over and grip a projecting tongue 42 integral with or attached to the end of the holder 32 remote from the pivotal stub 36.

When the holder 32 is not in use it is compactly and neatly stored away on the upper face of the aforesaid plate or leaf 27 and is prevented from displacement by spring grips 43 upstanding from the latter, while said holder 32 is provided on its back-side with offset flanges 44 which can be seated over a laterally projecting T-shaped projection 45 secured at one of the angular corners of the casing or box 10 in any of the well known ways. Now when it is desired to sharpen a blade the holder 32 is turned upside down on the plate or leaf 27 with the edge of said blade on the roller 17, and the back edge 35, of the holder 32 abutting spaced projections or upstanding tongues 46 on the plate 27, while the locking member 39 is gripped at its ends by the spring tongues 31 whereupon the handle 23 is withdrawn and rotated to thoroughly strop or sharpen the blade 29.

35 A tongue or knob 47 is provided on the leaf or plate 27 remote from the hinge 26 whereby said plate can be raised to take out or replace a blade 29.

To use the razor for shaving purposes after a blade 29 has been inserted in the holder 32 all that is necessary is to simply close the lid 11 on the box or casing 10 and attach the said holder on the T-shaped projection from either side by the offset flanges 44 as clearly shown in Fig. 4, the closed box serving as a handle by means of which the razor can be easily manipulated.

In order to provide means for renewing the sharpening or stropping roller 17, I may make one or both of the bearings 15 integral with a removable member 48 which can be drawn out whereupon the spindle or shaft 16 can be easily removed and a new roller 17 placed thereon in any of the well known ways, and 49 indicates a spring catch on the box 10 for engagement with the flange 50 on the cover 11 to lock the device in closed or out of use position.

From the foregoing description the use and operation of my improved safety razor stropping device will be clearly apparent without further elucidation and while I have described and shown one practical and preferred embodiment thereof I wish 65 it clearly understood that various detail

changes and other combinations thereof may be easily effected without in any way departing from the spirit and scope thereof, or as more particularly defined by the appended claims.

Having described my invention what I claim as new and desire to secure by Letters Patent is:—

1. A safety razor including a receptacle, a cover hinged to said receptacle, a blade carrier hinged in said receptacle, sharpening means operably mounted in said receptacle, a mirror carried by the hinged cover, and a blade holder adapted to seat on the blade carrier and to be removably attached to the receptacle when the operation of shaving is to be effected.

2. A safety razor including a box-like casing, a cover hinged to said casing, a mirror detachably supported in said cover, a blade carrier hinged in said casing, a stropping roller revolvably mounted in said casing, collapsible means for operating said stropping roller when desired, a blade holder adapted to retain a blade in shaving position therein, said blade holder being adapted to seat in locking engagement on the blade carrier when not in use and arranged for removable attachment on the casing when the operation of shaving is to be effected.

3. In a safety razor comprising a box-like casing, a cover hinged to said casing, a mirror detachably supported in said cover, the combination of a blade carrier consisting of a hinged plate having spring clamps and depending flanges there beneath for holding a series of blades and spring clips on its upper face, a blade holder adapted to seat on and be retained in out-of-use position by the spring clips on the aforesaid carrier, said blade holder being adapted to retain a blade in shaving position therein and arranged for removable attachment on the casing when the operation of shaving is to be effected, a stropping roller revolvably mounted in the casing, and collapsible means for operating said stropping roller when desired.

4. In a safety razor comprising a box-like casing, a cover hinged to said casing, a mirror detachably supported in said cover, the combination of a blade carrier consisting of a hinged plate having spring clamps and depending flanges there beneath for holding a series of blades and spring clips on its upper face for holding the plate in position, a blade holder consisting of a plate having a scalloped edge and an opposed upstanding flange, curved upstanding opposed flanges at the ends thereof for seating the ends of the blade therein, a locking member hinged to said plate and having clamping springs adapted to engage and grip the blade, a turned over tongue on the locking

- member for engaging a projection on the plate to lock the blade in adjusted position, said blade holder being adapted to seat on and be retained in out-of-use position by the 5 spring clips on the aforesaid carrier and arranged for removable attachment on the casing when the operation of shaving is to be effected, a stropping roller revolvably mounted in the casing, and collapsible means 10 for operating the stropping roller when desired.

5. In a safety razor comprising a box-like casing, a cover hinged to said casing, a mirror detachably supported in said cover, the 15 combination of a blade carrier consisting of a hinged plate having spring clamps and depending flanges there beneath for holding a series of blades and spring clips on its upper face for holding the plate in position, a blade holder consisting of a plate having a scalloped edge and an opposed upstanding flange, curved upstanding opposed flanges at the ends thereof for seating the 20 ends of the blade therein, a locking member hinged to said plate and having clamping springs 25 adapted to engage and grip the blade, a turned over tongue on the locking member for engaging a projection on the plate to lock the blade in adjusted position, said blade holder being adapted to seat on and be retained in out-of-use position by the 30 spring clips on the aforesaid carrier and arranged for removable attachment to a hinged T-shaped projection on the casing 35 when the operation of shaving is to be effected, a stropping roller revolvably mounted in the casing, and collapsible means for operating the stropping roller when desired.

6. In a safety razor comprising a box-like 40 casing, a cover hinged to said casing, a mirror detachably supported in said cover, the combination of a blade carrier consisting of a hinged plate having spring clamps and depending flanges there beneath for holding 45 a series of blades and spring clips on its upper face for holding the plate in position, a blade holder consisting of a plate having a scalloped edge and an opposed upstanding flange, curved upstanding opposed flanges 50 at the ends thereof for seating the ends of the blade therein, a locking member hinged to said plate and having clamping springs 55 adapted to engage and grip the blade, a turned over tongue on the locking member for engaging a projection on the plate to lock the blade in adjusted position, said blade holder being adapted to seat on and be retained in out-of-use position by the 60 spring clips on the aforesaid carrier and arranged for removable attachment to a hinged T-shaped projection on the casing 65 when the operation of shaving is to be effected, a stropping roller revolvably mounted in the casing and having its spindle extending into a cellular end portion thereof, a sleeve having a pin and slot connection on the 70 extended portion of the spindle, an arm carried by the sleeve, and a handle hinged to the free end thereof whereby the roller may be operated to effect the stropping of a blade. 75

7. In a safety razor comprising a box-like casing, a cover hinged to said casing, a mirror detachably supported in said cover, the combination of a blade carrier consisting of a hinged plate having spring clamps and depending flanges there beneath for holding a series of blades and spring clips on its upper face for holding the plate in position, a blade holder consisting of a plate having a scalloped edge and an opposed upstanding flange, curved upstanding opposed flanges at the ends thereof for seating the ends of the blade therein, a locking member hinged to said plate and having clamping springs 80 adapted to engage and grip the blade, a turned over tongue on the locking member for engaging a projection on the plate to lock the blade in adjusted position, said blade holder being adapted to seat on and be retained in out-of-use position by the 85 spring clips on the aforesaid carrier and arranged for removable attachment to a hinged T-shaped projection on the casing 90 when the operation of shaving is to be effected, a stropping roller revolvably mounted in the casing and having its spindle extending into a cellular end portion thereof, a sleeve having a pin and slot connection on the extended portion of the spindle, an arm carried by the sleeve, and means for locking 95 the blade carrier in closed position.

8. In a safety razor comprising a box-like casing, a cover hinged to said casing, a mirror detachably supported in said cover, the combination of a blade carrier consisting of a hinged plate having spring clamps and depending flanges there beneath for holding a series of blades and spring clips on its upper face for holding the plate in position, a blade holder consisting of a plate having 100 a scalloped edge and an opposed upstanding flange, curved upstanding opposed flanges at the ends thereof for seating the ends of the blade therein, a locking member hinged to said plate and having clamping springs 105 adapted to engage and grip the blade, a turned over tongue on the locking member for engaging a projection on the plate to lock the blade in adjusted position, said blade holder being adapted to seat on and be retained in out-of-use position by the 110 spring clips on the aforesaid carrier and arranged for removable attachment to a hinged T-shaped projection on the casing 115 when the operation of shaving is to be effected, a stropping roller revolvably mounted in the casing and having its spindle extending into a cellular end portion thereof, a sleeve having a pin and slot connection on the extended portion of the spindle, an arm 120 carried by the sleeve, and means for locking the blade carrier in closed position.

9. In a safety razor comprising a box-like casing, a cover hinged to said casing, a mirror detachably supported in said cover, the combination of a blade carrier consisting of a hinged plate having spring clamps and depending flanges there beneath for holding a series of blades and spring clips on its upper face for holding the plate in position, a blade holder consisting of a plate having a scalloped edge and an opposed upstanding flange, curved upstanding opposed flanges at the ends thereof for seating the ends of the blade therein, a locking member hinged to said plate and having clamping springs 125 adapted to engage and grip the blade, a turned over tongue on the locking member for engaging a projection on the plate to lock the blade in adjusted position, said blade holder being adapted to seat on and be retained in out-of-use position by the spring clips on the aforesaid carrier and arranged for removable attachment to a hinged T-shaped projection on the casing 130 when the operation of shaving is to be effected, a stropping roller revolvably mounted in the casing and having its spindle extending into a cellular end portion thereof, a sleeve having a pin and slot connection on the extended portion of the spindle, an arm

carried by the sleeve, and means on the blade carrier for holding the blade holder in reversed or upside down position during the stropping operation.

5 9. In a safety razor comprising a box-like casing, a cover hinged to said casing, a mirror detachably supported in said cover, the combination of a blade carrier consisting of a hinged plate having spring clamps and dependent flanges there beneath for holding a series of blades and spring clips on its upper face for holding the plate in position, a blade holder consisting of a plate having a scalloped edge and an opposed upstanding flange, curved upstanding opposed flanges at the ends thereof for seating the ends of the blade therein, a locking member hinged to said plate and having clamping springs adapted to engage and grip the blade, a

turned over tongue on the locking member 20 for engaging a projection on the plate to lock the blade in adjusted position, said blade holder being adapted to seat on and be retained in out-of-use position by the spring clips on the aforesaid carrier and 25 arranged for removable attachment to a hinged T-shaped projection on the casing when the operation of shaving is to be effected, a stropping roller revolvably mounted in the casing and having its spindle extending into a cellular end portion thereof, a sleeve having a pin and slot connection on the extended portion of the spindle, an arm carried by the sleeve, means for raising and lowering the blade carrier, and means for 30 locking the casing when closed.

In testimony whereof I affix my signature.
JAMES A. MALONEY.
